UNITED STATES PATENT OFFICE

151,705

DESIGN FOR A TEXTILE FABRIC

Edmund M. Patterson, New York, N. Y.

Application October 23, 1947, Serial No. 142,106

Term of patent 7 years

(Cl. D92—1)

To all whom it may concern:

Be it known that I, Edmund M. Patterson, a citizen of the United States of America, residing in New York city, county of New York, and State of New York, have invented a new, original, and ornamental Design for a Textile Fabric, of which the following is a specification, reference being had to the accompanying drawing, forming part thereof, wherein the figure is a plan view of a textile fabric showing my new design.

The dot and dash lines on the drawing outline a design unit, which unit is repeated in regular succession as indicated by the extensions beyond the unit boundaries.

I claim:

The ornamental design for a textile fabric, substantially as shown and described.

EDMUND M. PATTERSON.
